UNITED STATES PATENT OFFICE.

CHARLES R. GREUTER, OF SAUGUS, MASSACHUSETTS.

CARBURETER.

1,272,036.

Specification of Letters Patent.

Patented July 9, 1918.

Application filed August 25, 1915. Serial No. 47,285.

To all whom it may concern:

Be it known that I, CHARLES R. GREUTER, a citizen of the United States, residing at Saugus, in the county of Essex and State 5 of Massachusetts, have invented certain new and useful Improvements in Carbureters, of which the following is a specification, such as will enable those skilled in the art to which it appertains to make and use the 10 same.

This invention relates to carbureters for use in connection with explosive engines using liquid fuel, and the object thereof is to provide a carbureter of this class which will 15 be simple in construction, efficient in operation, and particularly to provide simple and efficient means for removing the needle valve in order that the parts may be cleaned without disturbing the adjustment and to provide 20 means whereby the needle valve may be adjusted with reference to the fuel nozzle within the range of the requirements of the carbureter, at the same time so limiting the range of the adjustment of the needle valve 25 that it cannot be forced against its seat on the fuel nozzle and the needle valve or its seat thereby injured or destroyed; to provide an indicator showing the adjustment of the needle valve with reference to the fuel 30 nozzle, so that if the adjustment becomes disturbed it may be readily readjusted by the operator. This and the other objects of my invention will more fully appear in the following specification, of which the accompanying 35 drawings form a part.

Certain features of the invention generally illustrated in the drawings and more or less fully described in the specification form the subject matter of my companion 40 application, Serial No. 47,284, filed August 25, 1915, for carbureters, and accordingly are not claimed herein.

Figure 1 is a sectional elevation of my invention; Fig. 2 a plan view, partly in section, showing one of the needle valves removed; Fig. 3 a detailed view of one of the needle valves and its housing; Fig. 4 a plan view, partly in section, of the needle valve, its housing and of that portion of the carbureter shell in which the needle and its housing is inserted; Fig. 5 a detailed view, partly in section, showing the means employed for locking the needle valve and its housing in the carbureter shell; Fig. 6 a plan 55 view of the needle valve; and Fig. 7 a plan

view of the needle valve with the indicator disk removed.

Similar characters designate similar parts throughout the accompanying drawings.

My carbureter as shown in the accompanying drawings is of the multiple type, and is provided with a shell or casing 1, having air intake openings 2 and 3, communicating with venturis 4 and 5, which discharge into a chamber 6. The casing is also provided 60 with a neck 7, in which is mounted a throttle valve 8, and the neck is provided with flanges 9, by which the carbureter is secured to the manifold. Each of the venturis is provided with a liquid fuel nozzle 10 in communication with a chamber 11, which is supplied with fuel from the float feed chamber 12. In chambers 13 in the walls of the casing 1 are mounted housings 14 which are secured in position by studs 15. The housings 14 are internally screw-threaded to receive the screw-threaded stems 16 of the tapered needle valves 17 which project into the nozzles 10 and are the means employed for regulating the supply of fuel. The housings 14 are each provided with a stop 18, on the disk-like head 19. The stem of the valve is provided with a disk shaped head 20, in which a number of screw-threaded holes 21 are formed. The periphery of the disk 20 is provided with grooves 20^a and a spring 22 is secured to the casing by a stud 23, the outer end of the spring 22 being held in contact with the periphery of the disk 20 with its rib 22^a in engagement with grooves 20^a 70 so as to prevent rotation of the disk except when the spring is withdrawn from the grooves of the disk. A disk 24 is secured on the outer face of the disk 20 by studs 25 and 26, stud 26 being of sufficient 75 length to project below the lower face of the disk 20, and contact with the stop 18 when the needle valve is rotated, thereby limiting the rotation of the needle valve and its adjustment with reference to its fuel nozzle. 80 To the outer end of the valve stem is secured a universal joint 27 to which is secured a rod 28, by means of which the needle valve may be rotated in its housing, and thereby adjusted 85 with reference to its fuel nozzle. The upper end of the venturi 4 is open to the chamber 6 and at its lower end it is provided with a weighted valve 29 which has a sliding movement on the guide stem 30. This valve 29 determines the vacuum in the ven- 90

turi 4. The venturi 5 is provided with a similar but lighter valve 31, slidably mounted on a guide stem 32. This valve 31 determines the vacuum under which the venturi 5 operates. At the upper end of the venturi 5 is a valve 33, adapted to close the upper end of the venturi 5. This valve is pivotally mounted at 34 upon an arm 35, pivotally mounted at 36. The weight of this valve 33 determines the vacuum which must be created in the chamber 6 before the venturi 5 and its nozzle are brought into action.

In assembling, the valves 17 are rotated in their housing until they are in contact with their seats in the throat of the fuel nozzles 10. They are then rotated slightly away from their seats and each stud 26 is next inserted in its screw-threaded hole 21, which is immediately to the right of the stop 18, and hence prevents the needle valve from being rotated so far as to bring it into contact with its seat in the throat of the fuel nozzle 10. The pitch of the threads on the valve stems is such that approximately one-half of a revolution of the needle valve will withdraw it sufficiently from its seat to cause its nozzle to supply the correct amount of fuel, and rotation of the valve, counter-clockwise, until the stud 26 is in contact with the opposite side of the stop 18, will cause its nozzle to supply an excessive amount of fuel, and the rotation of the valve in the opposite or clockwise direction until the stud 26 comes into contact with the stop 18 will cause the nozzle to supply an inadequate amount of liquid fuel. The stop and stud, however, provide adequate range for adjustment and prevent the turning down of the needle valve far enough to bring it into contact with its seat, and thereby prevents injury to the needle valve and its seat by inexperienced operators. When the needle valve has been adjusted its position is easily determined by the scale on the dial 24, and if the adjustment is disturbed it can be readily restored by the operator. The dial 24 should be so located or placed in position on the head 20 that when the stud 26 is in contact with the right hand side of the stop 18 and the flow of fuel is practically shut off, zero on the dial will be opposite the rib on the spring 22 which engages with the grooves in the periphery of the head 20. The lower ends of the studs 25 are then upset so that they can not afterward be removed, and the stud 26 is flattened near the lower face of the disk 20 so that it can not afterward be removed, making the range of adjustment permanent. After the carbureter has been accurately adjusted the reading on the dial may be stamped on the raised boss 37 so that it may always be readily restored to the proper adjustment by the operator.

65 The needle valves and their housings can

be readily removed by withdrawing them from the casing after the stud 15 has been removed and without disturbing the adjustment. The studs 15 act not only as a means for securing the needle valves and their 70 housings in the casing 1, but for securing them in the casing in the exact position which they occupied before they were withdrawn. The rod 28 serves as a convenient means for adjusting the needle valve to 75 which it is attached and may be extended to a convenient location as, for instance, the dash of the car to the engine of which the carbureter is attached, so that the adjustment may be made when the car is running. 80

By the employment of nozzles 10 in the form of readily removable nipples, I am enabled to construct and assemble the carbureter with great facility, and in the event 85 of a nipple becoming clogged or injured, can readily replace it by another. I may also substitute one of larger or smaller outlet in case this be desirable. By having the needle valve enter the tip of the nozzle, it is made 90 to aid in the diffusion or spreading of the liquid jet emerging from the nozzle.

The internal threading of the housings 14 to receive the threaded stems of the needle valves, and the arrangement of the housings 95 to slide freely into close fitting sockets and locking them in place by pins 15, insures the unvarying seating of the housings and all carried thereby, since the pins can only be inserted when the housings are fully 100 seated within their sockets and turned to the precise position to cause registration of the pin recess formed partially in the housing and partially in the shell or body of the carbureter. Upon removing either pin the 105 housing which it locks in place may be withdrawn without in any manner disturbing the adjustment of the needle valve, and with the ability to re-position or adjust the needle valve absolutely and unfailingly in case it 110 be turned in any degree whatever while the housing is dismounted. When once adjusted, the needle valve can not under any circumstances be forced into actual contact with the nozzle, hence can not possibly injure said nozzle, nor so completely close it 115 as to prevent a limited amount of fuel escaping in the act of starting the motor to which the carbureter is applied.

Having described my invention what I 120 claim as new is:

1. A carbureter comprising, in combination, a casing; a fuel nozzle mounted therein; a removable housing seated in a socket in said casing in axial alinement with said nozzle; a needle valve longitudinally adjustable in said housing and in axial relation thereto; a retaining device for said housing capable of application only when the housing is in its precise predetermined 130

- position; and a stop carried by the housing and co-acting with said needle valve to limit the movement of the latter toward said nozzle.
- 5 2. In a carbureter, the combination of a casing provided with a socket to receive a housing; a housing removably mounted in said socket; a needle valve longitudinally adjustable in said housing; a fuel nozzle 10 mounted in the casing in axial alinement with the needle valve; a stop carried by the housing; and a co-acting stop carried by the needle valve, said stops serving by their co-action to limit the movements of the 15 needle valve both toward and from the fuel nozzle, and said housing being made to closely fit within its socket and being held therein by a pin insertible only when the housing is perfectly seated in its predetermined position.
- 20 3. In a carbureter, the combination of a shell or casing provided with a fuel nozzle;
- a socket in said casing in axial alinement with said nozzle; a housing adapted to fit accurately in said socket and provided with 25 a stop; a needle valve longitudinally adjustable in said housing and provided with a stop arranged to co-act with the stop on the housing, and serving to limit the movement of the needle valve in its housing toward and from the nozzle; and a fastening 30 for holding the housing in its socket, capable of application only when the socket is fully seated in its predetermined position, the housing, needle valve and stops being removable bodily from the casing and without relative movement between themselves.
- 35 Signed at Saugus, in the county of Essex and State of Massachusetts, this 19th day of August, 1915.
